BOTTLE

Brooks D. Fuerst, Toledo, Ohio, assignor to Owens-Illinois, Inc., Toledo, Ohio, a corporation of Ohio

Filed Mar. 4, 1968, Ser. No. 10,840

Term of patent 14 years

Int. Cl. D9—01

U.S. Cl. D9—105

FIG. 1

The dominant features of the design reside in the portions shown in full lines.

I claim:

The ornamental design for a bottle, substantially as shown and described.
